His Attorney.

UNITED STATES PATENT OFFICE.

ALEXANDER MARION REEVES, OF BUDA, TEXAS.

TIRE-TIGHTENER.

SPECIFICATION forming part of Letters Patent No. 449,234, dated March 31, 1891.

Application filed October 25, 1890. Serial No. 369,382. (No model.)

To all whom it may concern:

Be it known that I, ALEXANDER MARION REEVES, a citizen of the United States, residing at Buda, in the county of Hays and State 5 of Texas, have invented certain new and useful Improvements in Tire Tighteners and Clamps; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 My invention has relation to improvements in tire-tighteners, and also to clamping devices used in connection therewith.

The invention consists in the improved construction and combination of parts, as hereinafter more fully set forth and described.

20 The object is to produce a device which will be most effective in operation and at the same time inexpensive of production, thereby reducing the cost to the minimum and saving 25 the expense of having tires shrunk in the ordinary way at blacksmith-shops.

In the accompanying drawings, Figure 1 is a side elevation of a portion of the rim of a wheel, showing my improved tightener applied thereto. Fig. 2 is a horizontal section. Fig. 3 is a detail view in perspective of the tightener, showing one of the plates removed or detached. Fig. 4 is a side elevation of a wheel, showing my improved clamps applied 35 thereto. Fig. 5 is a cross-section on the line $x x$, Fig. 4; and Fig. 6 is a detail view of one member of the clamps in perspective and looking from the inner side.

Like letters of reference refer to like parts 40 throughout the several views.

Referring to the drawings, the letter A indicates the wheel, B the spokes, and C the fellyes. The wedge proper is indicated by the letter D, and consists, preferably, of an 45 oblong block formed upon opposite sides with central longitudinal ridges or semicircular ribs $d d$. These ridges or ribs, it will be noticed by reference to Figs. 2 and 3 of the drawings, are wedge-shaped or taper from 50 the point d' to the point d^2 . When the block is inserted in the felly-joint, as hereinafter

more fully explained, plates E E of oblong or other suitable shape are made to embrace opposite sides of the wheel-rim and secured to the pins d^3 by bradding or riveting, and thus 55 serve to retain the wedge in place and prevent any lateral displacement.

In Figs. 4, 5, and 6 of the drawings I have illustrated my improved clamping device used in connection with the tightener. This device constitutes four metallic pieces F, and as each piece is similar in all respects, so far as construction is concerned, for the sake of convenience only one will be described. This consists of an arm or clamping-plate having 60 at one end an angular extension f , which protrudes above the rim of the wheel, and provided at its opposite end with a slight downward extension f' , while its inner face is corrugated or ribbed, as indicated by the letter f^2 . Both the angular extension and the downward extension are provided with bolt-holes f^3 and f^4 , respectively. The clamps are intended 65 to be applied to the wheel upon each side of the felly-joint or where the wedge is inserted. 70 They are arranged on each side of the joint in pairs, two of the plates being upon the inside of the rim and two on the outside with the fluted or corrugated faces against the sides of the rims. Bolts G G are then passed 75 through the registering holes or apertures of the downward and angular extensions, said bolts being provided with screw-threaded ends to receive nuts H, which are screwed up tight, so as to prevent slipping of the clamps when 80 the wedge is driven in between the same. The object of these clamps is to force the felly-joint open, so that the wedge D may be readily inserted, and this object is accomplished 85 in the following manner: The clamps being 90 arranged in the manner illustrated in Fig. 4, a wedge consisting, preferably, of two pieces of wood, as indicated in dotted lines, is forced into the space between the ends of the clamps, and as these wedges are driven "home" said 95 clamps will have the effect of forcing the felly-joint open, inasmuch as they are firmly held to the rim, both by the bolts G and the serrated faces. After the joint has been forced open sufficiently the wedge D may then 100 be readily inserted. After the block is thus adjusted the plates E are then secured, which,

it will be observed, serve the twofold purpose of preventing displacement of the wedge and holding the ends of the fellies to their place.

It will of course be understood that the wedge is inserted at the joint transversely to the rim of the wheel, though of course it could be forced in place vertically. In that case, however, it would not only leave one of the plates standing out from the periphery of the wheel, thus tending to produce uneven riding, but would also necessitate puncturing the tire to permit of one of the pins d^3 passing therethrough. These of course would be serious disadvantages, and I therefore prefer to insert the wedge in the manner illustrated in the drawings, although I do not wish to be understood as limiting myself to that particular mode of application.

It will be seen from the foregoing description that my improved tightener is exceedingly simple in construction and easy of application, and possesses among other advantages the facility of overcoming the probability of great damage arising from the tightening of the tire too much.

Having thus described my invention, what I

claim, and desire to secure by Letters Patent of the United States, is—

1. A wedge for tightening vehicle-tires, consisting of a body portion provided with longitudinal ridges or webs, substantially as set forth. 30

2. A wedge for tightening vehicle-tires, consisting of a body portion provided with longitudinal tapering ridges or webs, substantially as set forth. 35

3. The combination, with a wheel-rim, of clamps arranged in pairs upon each side of the felly-joint, said clamps consisting of plates having a fluted or corrugated inner 40 surface, and provided at one end with an angular upward extension and at the opposite end with a downward extension, the extension of the registering plates being connected by transverse bolts, substantially as set forth. 45

In testimony whereof I affix my signature in presence of two witnesses.

ALEXANDER MARION REEVES.
